(57) **CLAIM**

The ornamental design for a lacrosse head, as shown and described.

DESCRIPTION

FIG. 1 is a top isometric perspective view of a lacrosse head showing the new design;

FIG. 2 is a front elevational view thereof;

FIG. 3 is a rear elevational view thereof;

FIG. 4 is a side elevational view thereof;

FIG. 5 is an opposite side elevational view thereof;

FIG. 6 is a top plan view thereof; and,

FIG. 7 is a bottom plan view thereof.

The broken lines and unshaded areas form no part of the claimed design. The solid lines in FIGS. 1-7 represent the claimed design of the front and rear edges of the lacrosse head, visible in their entireties in the profiles of FIGS. 2 and 3, respectively. The unshaded areas immediately adjacent to the solid lines form no part of the claimed design.
